UNITED STATES PATENT OFFICE.

FREDERICK WATSON BACH, OF NEW BOND STREET, COUNTY OF MIDDLESEX,
ENGLAND.

DESIGN FOR A LAMP-SHADE.

SPECIFICATION forming part of Design No. 16,911, dated September 28, 1886.

Application filed August 12, 1886. Serial No. 210,742. Term of patent 3½ years.

To all whom it may concern:

Be it known that I, FREDERICK WATSON BACH, a subject of the Queen of Great Britain, residing at New Bond Street, in the county of Middlesex, England, have invented or produced a new and original design for Hollow Globes or Shades for Lamps, of which the following is a full, clear, and exact description.

The design is illustrated in the accompanying drawings, in which Figure 1 is a side elevation of a lamp globe or shade made according to my design, and Fig. 2 a top plan view of the same.

In the drawings, the letter *b* indicates the base ring or band, having a lower open end,

arranged in a horizontal plane and surmounted at its upper portion by the vertical body *a*, having the configuration of a tulip-blossom.

Having thus fully described my invention, what I claim is—

The design for a hollow lamp globe or shade, consisting of a base ring or band, *b*, surmounted by the body *a*, having the configuration of a tulip-blossom, open at its base, substantially as described and shown.

FREDERICK WATSON BACH.
